CLAIM

We claim the ornamental design for a slim wallet with built-in battery, as shown and described.

DESCRIPTION

FIG. 1 is a perspective view of a slim wallet with built-in battery, showing our new design with cable in tucked-in position;

FIG. 2 is a top plan view thereof;

FIG. 3 is a bottom plan view thereof;

FIG. 4 is a right elevational view thereof;

FIG. 5 is a left elevational view thereof;

FIG. 6 is a front elevational view thereof;

FIG. 7 is a back elevational view thereof;

FIG. 8 is a perspective view thereof showing built-in cable in tucked-in position; and,

FIG. 9 is a perspective view thereof showing built-in cable untucked from pouch.

The broken lines depict unclaimed portions of the wallet.

1 Claim, 9 Drawing Sheets
